ABRADING MACHINE

John B. Hadaway, Swampscott, Mass., assignor
to United Shoe Machinery Corporation, Paterson, N. J., a corporation of New Jersey

Application October 18, 1932, Serial No. 638,281

13 Claims. (Cl. 69—1)

This application relates to abrading machines and is herein illustrated as embodied in a machine for roughening channels and channel flaps formed in shoe parts.

5 In the manufacture of certain types of shoes, for example, Goodyear shoes, it is customary to produce a channel on the tread face of an outsole by cutting and raising a flap along the edge thereof, and to attach the outsole to the upper by a row of stitches which pass through the bottom of this channel. The flap is then cemented to the channel to cover the stitches. However, before cementing the flap it is usual to perform a rubbing operation upon the stitches to cause them to lie flat. This rubbing operation tends to glaze the surface of the channel and to pack down the fiber of the leather so close as to prevent the adhesive gaining a proper hold of the leather on the channel flap and in the channel.

20 It is an object of the present invention to provide an improved machine for roughening channels and channel flaps formed upon shoe parts to facilitate the cementing of the flaps to the channels.

25 In accordance with a feature of the invention, the illustrated embodiment of the invention comprises a substantially cylindrical scouring tool for scouring channels and a conical scouring tool for scouring channel flaps, both tools being mounted upon the same shaft. In the illustrated machine, the scouring tools of which consist of wire brushes, the work is guided to the tools by a gage which extends between the cylindrical and the conical tools. The illustrated gage consists of a thin blade-like member adapted to engage the shoulder of the channel, and this gage is mounted for adjustment toward and from or transversely of the shaft. The gage serves not only as above-stated to guide the work in relation to the scouring tools but also to limit the pressure between the work and the tools, that is, to limit the extent to which the wire bristles of the roughening tools can be deformed under pressure of the work.

40 A further feature of the invention consists of the provision of means for holding the relatively flexible flap against a roughening tool. In the illustrated machine the flap-holding means consists of a frusto-conical roll which engages the outside of the flap and which is resiliently pressed toward the roughening tool.

45 These and other features of the invention including certain details of construction and combinations of parts will be described in connection with the illustrated machine and pointed out 50 in the appended claims.

Referring now to the accompanying drawing, Fig. 1 is a view in front elevation of a machine in which the present invention is embodied showing the channel and the channel flap of an outsole in the process of being roughened; and

5 Fig. 2 is a side elevation of the machine shown in Fig. 1.

The supporting structure of the machine consists of a hollow frame 10 adapted to rest upon the floor and to support a head 12 which carries a pair of spaced bearings 14 for a shaft 16. Mounted upon the shaft 16 are a pair of fixed and loose pulleys 18 and 20 respectively for engagement with a driving belt 22. Adjacent to an end of the shaft 16 is a frusto-conical scouring brush 24 having wire bristles. A substantially cylindrical scouring brush 26 also having wire bristles and of a diameter substantially equal to that of the large end of the brush 24 is also mounted of the shaft 16. The brush 26 is spaced from the end of the shaft 16 and is adjacent to but spaced a slight distance from the large end of the brush 24. Extending into the space between the brushes 24 and 26 is a gage which consists of a thin blade-like member 28. The upper end of the member 28 has formed in it a slot 29 through which extends a clamping screw 32 for clamping the member 28 to a bracket 30 which is secured on one of the bearings 14. The member 28 curves downwardly and inwardly from its locality of attachment to the bracket 30 so that the lower end of the member 28 is underneath the shaft 16 and between the brushes 24 and 26. The distance between the lower end of the member 28 and the shaft 16 can be adjusted by loosening the screw 32 and sliding the member 28 up or down until the desired adjustment has been obtained, after which the screw 32 may be tightened. The bracket 30 is secured to the bearing 14 by a clamping screw 34 which extends through a horizontal slot 36 formed in the bracket 30. Interposed between the head of the screw 34 and the bracket 30 is a washer 38. Such provision for horizontal adjustment of the bracket 30 enables the position of the gage member 28 to be adjusted 35 in a direction lengthwise of the shaft 16 for different combinations of scouring brushes.

40 In order to hold a relatively flexible channel flap against the frusto-conical brush 24, there is provided a frusto-conical roll 40 which engages the outside of the channel flap and presses the flap against the brush 24. The roll 40 is mounted upon the end of a shaft 42 which is journaled in bearings 44 formed in a forked lever 46. The lever 46 is journaled on a pin 48 carried in a 45 50 55

bracket 50 which is secured to the head 12 of the machine. The lever 46 has a horizontally extending bell crank arm 52. A rod 54 is pivotally connected at its upper end to an end of the arm 52, 5 the lower end of the rod 54 being pivotally connected to an end of a lever 56 which is fulcrumed upon a pin 58 secured in the head 12. The treadle rod 60 connects the lever 56 to a treadle 62 which is fulcrumed upon a pin 64 secured in the 10 lower portion of the machine frame 10. Formed in the bracket 50 is a well 66 which receives and constitutes an abutment for the lower end of a coil compression spring 68. An abutment 70 for the upper end of the spring 68 is carried upon 15 the lower end of a screw 72 which is threaded through a lug 74 formed in the bell crank arm 52. A head 76 upon the screw 72 provides for adjustment of the pressure of the spring 68. The approach of the roll 40 toward the scouring tool 24 20 is limited by a stop screw 78 which is threaded through a lug 80 formed in the bracket 50. An end of the screw 78 engages a lug 82 formed upon the lever 46.

The operation of the above-described machine 25 is illustrated in Fig. 1 wherein is shown a lasted shoe S having formed in its outsole a channel C and a flap F. The operator presents the shoe to the machine with the bottom of the channel C engaging the brush 26 and the inner surface of the flap F engaging the brush 24. The gage member 28, by engagement with the shoulder of the channel, as shown in Fig. 1, enables the operator to guide the shoe in proper relation to the scouring tools and it also serves to prevent 30 excessive deformation of the bristles of the scouring tools. The roll 40 serves to hold the flexible flap F against the tool 24. When the operation has been finished the operator depresses the treadle 62 and thereby separates the roll 40 from 40 the tool 24 to enable the flap of a succeeding shoe to be presented to the tool 24. He thereupon releases the treadle 62 and repeats the operation with the succeeding shoe.

Having described the invention, what I claim 45 as new and desire to secure by Letters Patent of the United States is:

1. A machine for scouring channels and channel flaps formed upon shoe parts, comprising a shaft, a substantially cylindrical scouring tool 50 on said shaft for scouring channels, and a conical scouring tool on said shaft adjacent to said cylindrical tool for scouring channel flaps.

2. A machine for scouring channels and channel flaps formed upon shoe parts, comprising a shaft, a substantially cylindrical wire brush on said shaft for scouring channels, and a frusto-conical wire brush on said shaft adjacent to said cylindrical brush for scouring channel flaps.

3. An abrading machine comprising a frame, 60 a shaft carried thereby, a pair of abrading tools mounted on said shaft, said abrading tools being separated from each other by a relatively narrow space, and a gage mounted on said frame independently of said shaft for guiding work presented to said abrading tools, said gage extending into the space between said abrading tools.

4. A machine for scouring channels and channel flaps formed upon shoe parts, comprising a substantially cylindrical wire brush, a frusto-conical wire brush adjacent to said cylindrical brush, driving means for said brushes, and a gage positioned between said brushes for engaging the shoulder between a channel flap and a channel 70 formed on a shoe part to guide the shoe part

with the channel flap in engagement with one of said brushes and the channel in engagement with the other of said brushes.

5. A machine for scouring channels and channel flaps formed upon shoe parts comprising a shaft, a pair of wire brushes mounted upon said shaft adjacent to each other, one of said brushes being substantially cylindrical for engagement with a channel and the other of said brushes being conical for engagement with a flap, and a thin 10 blade-like gage member interposed between said brushes for engagement with the shoulder of the channel to guide the shoe part upon which the channel and the flap are formed.

6. An abrading machine comprising a shaft, a 15 pair of abrading tools mounted on said shaft, a gage positioned between said abrading tools for guiding work, and supporting means for said gage constructed and arranged to enable said gage to be adjusted toward and from said shaft. 20

7. A machine for scouring channels and channel flaps formed on shoe parts, comprising means for scouring simultaneously a channel and a channel flap formed on a shoe part and means for holding the channel flap against said scouring 25 means while the channel is presented to said scouring means.

8. A machine for scouring channels and channel flaps formed on shoe parts, comprising a shaft, a substantially cylindrical wire brush on 30 said shaft, a frusto-conical wire brush on said shaft adjacent to said cylindrical brush, and means for pressing a channel flap on a shoe part against said frusto-conical brush while the channel of the shoe part is presented to said cylindrical brush. 35

9. A machine for scouring channels flaps formed upon shoe parts, comprising a frusto-conical scouring brush and a roll constructed and arranged to press a channel flap against said 40 scouring brush.

10. A machine for scouring channel flaps formed upon shoe parts, comprising a frusto-conical scouring brush, a frusto-conical roll, and resilient means acting upon said roll to cause 45 said roll to press a channel flap against said scouring brush.

11. A machine for scouring channels and channel flaps formed on shoe parts, comprising a plurality of wire bristles constructed and arranged to scour simultaneously a channel and a channel flap formed on a shoe part, a roll engageable with the channel flap, a pivotal support for said roll, a spring acting upon said support to cause said roll to press the channel flap against 50 said scouring bristles, and operator controlled means for separating said roll and said scouring bristles to facilitate the introduction of a channel flap therebetween.

12. A machine for scouring channel flaps on 60 shoe soles comprising a scouring tool constructed and arranged to operate upon the inner surface of an upturned channel flap, and a gage engageable with the shoulder of the channel for controlling the presentation of the flap to said scouring tool.

13. A machine for scouring channel flaps on 70 shoe soles comprising a scouring tool constructed and arranged to operate upon one surface of a channel flap, and means engageable with the opposite surface of the flap to hold the flap against said scouring tool.

JOHN B. HADAWAY.
